UNITED STATES PATENT OFFICE

102,544

DESIGN FOR A LIGHTING FIXTURE

Arthur R. Butterworth, Los Angeles, Calif., assignor to Solar Lighting Fixture Company, Los Angeles, Calif., a corporation of California

Application July 21, 1936, Serial No. 63,964

Term of patent 7 years

To all whom it may concern:

Be it known that I, Arthur R. Butterworth, a citizen of the United States, residing at Los Angeles, in the county of Los Angeles and State of California, have invented a new, original, and ornamental Design for a Lighting Fixture, of which the following is a specification, reference being had to the accompanying drawing forming part thereof, in which

Fig. 1 is a top plan view, the support shown in Figs. 2 and 3 being omitted.

Fig. 2 is an elevational view.

Fig. 3 is a vertical section taken on the line 3—3

of Fig. 1 of a lighting fixture showing my new design.

The characteristic features of my design reside in the three annular louvers, each provided with a rolled peripheral edge, the body of each louver being curved inwardly and downwardly, said louvers being spaced from each other and progressively smaller in diameter, the largest being on top.

I claim:

The ornamental design for a lighting fixture, as shown and described.

ARTHUR R. BUTTERWORTH.
